Application January 1, 1942, Serial No. 425,321

1 Claim. (Cl. 183—35)

This invention relates to power units for collecting dust and fine material removed from articles as by lathes, grinders, or polishers.

This invention has utility when incorporated in dental and industrial equipment for gathering fragments or portions removed from dentures and sections from articles of work.

Referring to the drawings:

Fig. 1 is a front view of an embodiment of the invention in a dental laboratory device;

Fig. 2 is a plan view of an increased filter capacity adaptation of the device of Fig. 1, with parts broken away;

Fig. 3 is a section on the line III—III, Fig. 1, showing the housing unit;

Fig. 4 is a fragmentary detail view of the device for mounting and removing the operating fixture from the power unit;

Fig. 5 is a section on the line V—V, Fig. 3, of the fan chamber and parts thereover in distributed relation;

Fig. 6 is a view of the rear of the device or unit, with parts broken away to show an additional feature of a knocker to clear the filter;

Fig. 7 is a view, with parts broken away, of an embodiment of the device as a bench fixture with the purifier or collector away from the tool;

Fig. 8 is a double end connection for the bench type of tool;

Fig. 9 is a section on the line IX—IX, Fig. 8, showing the hood adjacent the tool and connected to the duct;

Fig. 10 is a wiring diagram of the unit and the purifier; and

Fig. 11 is a fragmentary detail of a flexible collector connection to a tool from the suction fan.

On a bench 1 is a motor 2 having a switch 3. The motor 2 has a shaft 4 upon which may be mounted a connection 5 for carrying a tool 6. Fixed with the housing of this motor 2 may be a threaded boss 7 (Fig. 4) about the shaft 4. On this threaded boss may be a nut 8 having a handle 9 to be rotated to travel away from the motor housing 2. The connection 5 and its tool 6 is thereby disconnected from the motor 2. There is thus provided ready means for mounting a cutting tool, grinding device, buffing or polishing fixture, as may be appropriate say in connection with dental work undertaken, whether for denture of the plate type, or for special forming of elements as teeth or fillings.

In the use of the present invention, this motor may have its shaft 4 located in proximity to an arc portion 10 (Fig. 3) of a hood 11 having a base portion 12 in which may be located a removable

tray 13. This hood is in proximity to a housing 14 having an inlet 15 to a multi-blade fan 16 on a shaft 17 of a motor 18 mounted on a deck 19 in the housing 14, spaced by a partition 20 from a fan chamber 21. About this inlet 15 to the multi-blade fan 16 extend yieldable, resilient spring arms 22 to engage peripherally a disk which constitutes a baffle. These arms 22 have overhanging free ends 24 notched to provide seat portions 25. There is, accordingly, positioning of this disk or baffle in spaced relation from the opening 15 to provide a peripheral intake 26 of an area desirably greater than that of the intake port 15. This baffle 23 has an offset upper portion 27 permitting the baffle as a unit to be removed from the spring arms 23 or placed against the intake 15, in thereby cutting off effective draft operation of the fan 16. At the position of normal placing of the baffle 23 in the spacing at the seats 25 there is a uniform distribution of air intake about this disk in thereby adapting the forward central more quiet region for building up particles deposited thereon in the form of a cone 28. This accumulation tends to drop into the tray 13. This tray 13 may save the fragments for reclaiming. In practice this collection of the coarse or major portions in advance of the fan has run from 85 to 90 per cent of the substance removed.

From the chamber 21 having a scroll housing 29 (Fig. 5) there is spill by port 30 to a tray 31 which constitutes a precipitation chamber. The rectangular shallow chamber above the tray 31 has screen side wall or mesh sections 32, 33, in a rectangular frame 34 having a filter filler 35 of fibrous material such as fine spun glass. The filter 35 may be adapted to remove fumes or odors, thru the use of special material therefor, such as charcoal, or activated carbon. The housing 14 has a cap 36 over this filter with louver ports 37 directed away from the hood. The chamber 31 accumulates a volume of the fines. A secondary accumulation is in front of the baffle or in the tray 13. There may be some deposit on the lower side of the filter. In fact, in removing the cap 36 it is in order to draw the finger nail across the screen 33 to loosen the accumulated material and cause it to drop into the tray 31. Upon removal of the filter there may be additional shaking thereof. However, its accumulation of the fines is so effective that the air discharged from the louvers or ports 37 is not dust laden.

On the housing is a switch 38 cut in connections 40 between power lines 39 and a bulb 41

which constitutes a light under the hood 11, thereby to illuminate the work exposed to the rotary tool 6. Simultaneously with this cutting in of the light 41, this switch 38 cuts in connections 42 to operate the motor 18 to drive the fan. Indentations 43 with outer overhang portions 44 provide hand holds.

The housing 14 may be placed on the floor or away from the bench and at the intake 15 there may be located a duct, say an elbow 45 (Fig. 7) to a down pipe 46 having an L-connection 47 with the hood 11. The duct 46 may have a branch 48 (Fig. 8) to an elbow 49 and a section 50 in communication by elbow 47 with a companion housing 11. The filter housing may be extended upward to enlarge its capacity.

A frame 14' has an upper chamber space with lateral or side louvers 52 (Fig. 2). Inward from the louvers 52 are filters 51, 53, about a tray 31'. The addition of side-wall filters thus provides increased area for low velocity escape and efficient separation of fragments, and accordingly, due to said increased area, there is less tendency to accumulate and obstruct the filter operation. This means a longer maintained efficient period of use.

Increased filter efficiency may be attained by the installation of a knocker device, herein shown as a crank shaft 54 protruding from the housing to have an operating handle 55 at one terminus and an adjusting wing nut 46 on an opposite threaded terminus 57 for regulating the position of this knocker to operate in so shaking the filter 35 that the fragments or particles removed from the air and lodged at such filter may be dropped therefrom into the tray 31.

According to the character of work in the use of the invention, the hood or housing 11 with its arc opening portion 10 expose the tool less to the eyes of the operator while he handles work at the tool. Accordingly, a hinge 58 (Fig. 9) may mount a shield 59 which may be a transparency. With the shield freely swung, the hands of the operator on the tool may locate the position of the shield or the hinge 58 may be held in posi-

tion by friction so that the depending shield is retained in position as adjusted.

From the fan unit, in lieu of the elbow 45 (Fig. 7) there may be a fitting of even the manifold type such as a flanged cap 60 (Fig. 11) having flexible ducts 61 therefrom to a hood or collector 62 about the tool 6. The particles to enter such passage way may be thrown off from work at a buffing or polishing jack, lathe, or other operating tools.

The installation according to the invention is one permitting ready placing, or when placed, use of the device in accumulating the particles which might contaminate the air. Furthermore, to the extent there be industrial values therein, such may be readily reclaimed. The coarser particles, by the draft in the hood, may be collected in advance of the fan due to the baffle 23. This low draft region may, to some extent, create a lower pressure or quiescent region effective for this deposit. Experience has shown that there may be this major accumulation on the baffle. The particles do not fly outward from the chamber, but, insofar as not collected on the baffle 23, pass by the clearance 26 through the intake port 15 to the centrifugal or multi-blade fan 15 for secondary deposit in the chamber 31. The cleared air passes therefrom by the filter and out the louver ports 37. A felt strip 51 is arranged marginally as a packing against any seepage of particles from about the filter.

What is claimed and it is desired to secure by United States Letters Patent is:

An air purifier unit embodying a suction fan of an endless annular series of blades forming an open ended cylinder, a housing for the fan providing an intake in cooperating proximity to the cylinder, a hood having an inlet opening of greater area than the fan intake, and a transverse baffle in the hood parallel to and spaced from the fan intake a sufficient distance to provide a uniform entrance way thereabout as great as the fan intake and on all sides of the baffle.
